SUPPORT FOR ASHTRAYS, AEROSOL CONTAINERS AND OTHER ARTICLES

Willard H. Sahloff, Bridgeport, Conn., assignor to Handy Andy Specialty Co., Inc., New York, N.Y.

Filed May 17, 1974, Ser. No. 470,774

Term of patent 14 years

Int Cl. D6—04

U.S. Cl. D6—86

FIG. 1

FIG. 2

FIG. 3

FIG. 5

FIG. 6

FIG. 4

FIG. 8

FIG. 7

FIG. 1 is a top plan view of a support for ashtrays, aerosol containers and other articles showing my new design;

FIG. 2 is a front elevational view thereof;

FIG. 3 is a side elevational view thereof;

FIG. 4 is a rear elevational view thereof shown on a reduced scale;

FIG. 5 is a top plan view of a second embodiment of the support for ashtrays, aerosol containers and other articles shown in FIG. 1;

FIG. 6 is a front elevational view thereof;

FIG. 7 is a side elevational view thereof; and

FIG. 8 is a rear elevational view thereof shown on a reduced scale.

I claim:

The ornamental design for a support for ashtrays, aerosol containers and other articles, as shown and described.
